Patented June 17, 1975

235,455

MULTIPLE LINE REMOTE DICTATION RECORDING STATION OR SIMILAR ARTICLE

David K. Walz, Atlanta, Ga., assignor to Lanier
Electronic Laboratory, Inc., Atlanta, Ga.

Filed Jan. 9, 1974, Ser. No. 432,056

Term of patent 14 years

Int. Cl. D14

U.S. Cl. D26—14 A

FIG 1

FIG 2

FIG 3

FIG. 4

FIG. 5

FIG. 6

FIG. 7

FIG. 1 is a perspective view of a multiple line remote dictation recording station embodying my new design;

FIG. 2 is a front elevation view of the multiple line remote dictation recording station;

FIG. 3 is a rear elevation view thereof;

FIG. 4 is a right side elevation view thereof;

FIG. 5 is a left side elevation view thereof;

FIG. 6 is a top plan view thereof; and

FIG. 7 is a bottom plan view thereof.

I claim:

The ornamental design for a multiple line remote dictation recording station or similar article, substantially as shown.
